FASTENING FOR THE HANDLES OF TOOLS

Daniel W. Winzeler, Montpelier, Ohio

Application June 14, 1934, Serial No. 730,642

1 Claim. (Cl. 306—29)

This invention relates to means for assembling metallic portions or sections with handles.

This invention has utility when incorporated with wood handles and collapsed cylindrical anchorage therewith of tool portions, extensions, 5 trims or ferrules.

Referring to the drawing:

Fig. 1 is a side view, with parts broken away, 10 of an embodiment of the invention as a trim, say for a fork handle, wherein the trim has a pair of tongues;

Fig. 2 is a fragmentary view of an embodiment of the invention in a tool having a tongue therefrom along the handle;

Fig. 3 is a section on the line III—III, Fig. 2;

Fig. 4 is an embodiment of the invention in association with metallic or sheet metal sleeve portions as a trim for a wood handle in the extensions from the grip of a D;

Fig. 5 is a view of an embodiment of the invention wherein the metal extension from the tool is of split sleeve form;

Fig. 6 is a view of the die for effecting a sequence of collapsing or diameter reduction assembly of the embracing cylinder herein for effecting anchorage;

Fig. 7 is a section on the line VII—VII, Fig. 1;

Fig. 8 is a section on the line VIII—VIII, Fig. 4; and

Fig. 9 is a section on the line IX—IX, Fig. 5.

Wood handle cylindrical portion 1 is shown with wood tapered portion 2 with which there may be telescopic assembly of ferrule tapering sleeve portion 3 having tongues 4, 5, therefrom.

At this telescopic assembly, loose ring 6 may be slipped to position in the general fitting relation of the tongues 4, 5, with the cylindrical portion 1 of the wood handle, whether or not the tongues 4, 5, have been pre-formed to the handle

40 or formed therewith after the telescopic assembly. Even in the latter instance, with offset marginal portions 7 embedded in the wood handle 1 as anchorage, there may be supplemental reinforcement in changing the relative diameter

45 of the ring 6 as to the wood 1 and tongue free termini. This herein may be effected by bringing the assembly with the loose ring 6 into position over die 8 having guides 9 rising therefrom to determine initial squeezing of the ring 6 to a reduced diameter, preferably less than the original diameter 1 plus the thickness of the ring 6 thereabout, now of oval form.

In this position upon the block or die 8, companion die 10 with guide way 11 for the guides 9 may approach this die 8 and at this press

operation effect the dimension reduction from oval of this ring 6 symmetrically throughout the circumference by a crowding, against ribbing or fluting action due to the distribution of the pressure action. In the suggested selection for dimension hereunder, there is supplemental embedding of the embraced portion of the free ends of the tongues, in that the ring 6 forms a partial seating thereinto compensated to some extent by the tongue embeddings being increased 5 at such region into the wood, while between the tongues there is partial embedding of the ring with the wood. This embracing is a reinforcement for the wood 1 as well as effecting this anchoring in a smooth relation for the handle so 10 that the operator is not subjected to wound the hand or tearing of hand covering in the normal operation of the tool as a fork or shovel. As 15 this anchorage is completed, assembly therewith of tool 12 as a fork may be had.

Whether or not the wood 1 be of a reduced 20 diameter or have tapered portion 2, there may be thrusting of the terminus 1 into socket, say in shovel 13. This shovel or tool blade 13 is shown with trim or tongue 14 therefrom seating along 25 the handle 1. Herein ring 15 may work its own seat partially into the free end of this tongue 14 as this ring is collapsed into the embedding assembly with the wood 1 in a manner analogous to that of the ring 6.

In the instance of D-handle grip 16 having sheet metal shield portions 17 in which may extend to a greater or less extent, wood fork portions 18 from the handle 1, there may be anchorage 30 assembly through collapsible cylindrical ring or 35 sleeve 19 analogous to the sleeve or rings 6, 15, with the collapsing effected in similar manner for forming the seat on the portions of the sheet metal forks 17 and increasing their embedding in the wood handle 1. This is an effective reinforcement 40 against any tendency of the split extension from the fork at the D to break.

Tapered wood handle portion 20 (Fig. 5) is shown of somewhat greater extent than the tapered portion 2 in Fig. 1. Taper ferrule portion 21 may be a forming of sheet metal from the tool approximating a split sleeve. Collapsible reinforcing ring 22 is herein shown extending longitudinally along the handle 1 beyond the terminus of the sheet metal portion 21, and in this 45 respect differs from the rings or sleeves 6, 15, 19. However, the collapsing is effected in a similar manner for seat forming and at the pressure anchorage therewith provides frictional effective 50 assembly.

What is claimed and it is desired to secure by Letters Patent is:

A handle for a tool, a sheet metal circumferentially incomplete portion in seating assembly with the handle, and an annularly complete ring embracing the handle and sheet metal portion

at said seat as a telescopic sleeve providing circumferential contracting means embedding the sheet metal portion with the handle, whereby the seat in the handle is formed for the sheet metal portion by contracting of the annular ring.

DANIEL W. WINZELER.
